UNITED STATES PATENT OFFICE.

ESTEBAN CIARLO, OF FOUNTAIN HILL, PENNSYLVANIA.

MECHANICAL MOVEMENT.

1,149,728.

Specification of Letters Patent. Patented Aug. 10, 1915.

Application filed August 14, 1912. Serial No. 715,051.

To all whom it may concern:

Be it known that I, ESTEBAN CIARLO, a citizen of Argentina, and resident of Fountain Hill, in the county of Lehigh and State 5 of Pennsylvania, have invented certain new and useful Improvements in Mechanical Movements, of which the following is a specification.

This invention relates to variable driving 10 mechanisms for use in multiple cylinder pumps or motors, whereby the stroke of the pistons may be varied to change the output of the pump or the speed of the motor, and is particularly applicable to variable speed 15 fluid transmission devices.

In variable speed fluid transmission devices a pump is used in connection with a hydraulic motor, the liquid passing directly from the pump cylinders into the motor cylinders to operate the motor. In order to vary the speed of the motor it is customary 20 in such devices to provide means for varying the stroke of the pump pistons, and in order to reverse the motor it is customary to reverse 25 the action of the pump pistons.

When the invention is used in connection with a variable speed fluid pressure motor, the motor receives a constant supply of the motive fluid and the piston displacement of 30 the motor is also constant. It will therefore be obvious that the speed of the motor will be inversely proportional to the stroke of the pistons.

The present invention has for its object 35 the provision of a mechanism which is simple in construction, is capable of transmitting considerable amounts of power, and which may be accurately and conveniently controlled.

40 The novel features of the invention will be apparent from the following description taken in connection with the accompanying drawings, in which the invention is shown as embodied in a multiple cylinder pump 45 adapted for use in a variable speed fluid transmission device.

In the drawings: Figure 1 is a longitudinal section through a pump embodying the invention; and Fig. 2 is a transverse section 50 on the line 2—2 of Fig. 1. Fig. 3 is an elevation of the main shaft.

Referring to the drawings, 10 designates 55 a frame which carries the pump cylinders 11, these cylinders being preferably arranged radially about the center of the driving shaft

12. The shaft 12 may have arranged on the projecting end 13 thereof a coupling, pulley or gear for the purpose of driving the same, and is hollow to receive the longitudinally movable wedge member 14. The shaft 12 is 60 provided with an integral flange 15, a removable flange 16 and a rectangular portion 12^a, the removable flange being held in position by means of a shoulder at 12^b, the end of the rectangular portion 12^a, and an eccentric 65 sleeve 17 and suitable nuts 18 and 19, the latter having screw-threaded engagement with the end of the shaft. The shaft 12 is carried in suitable bearings 20 and 21 and has arranged thereon a thrust collar 22 70 which is held in position by a suitable sleeve 23 having threaded engagement with the shaft. On the opposite sides of the thrust collar 22 are arranged the thrust bearings 24 and 25, the thrust bearing 24 engaging a 75 shoulder 26 on the bearing member 27 carried by the frame 10, and the bearing 25 being secured in position by a cap or bonnet 28 which may be secured to the bearing member 27 by means of screw threads 29, or in 80 any other suitable manner, and which carries suitable packing means 28' surrounding the shaft.

Each of the pump cylinders 11 has co-operating therewith a valve 30 arranged in 85 a cylinder 31 connected with the cylinder 11 by a suitable conduit 32. The eccentric sleeve 17 may be rigidly secured to the shaft 12 and has arranged thereon a bearing sleeve 33 provided with an inturned concentric flange 34 which co-operates with a similar flange 35 on the nut 36 to hold the eccentric strap 37 in position, the strap being provided with laterally projecting flanges 38 and 39 which co-operate with the above-men- 90 tioned flanges 34 and 35. The eccentric strap 37 is provided with the radially ex-tending arms 40 which are connected with the valves 30 by means of pins or pivots 41. 95

Each of the cylinders 11 is provided with 100 a piston 42 and these pistons are preferably actuated by means of connecting rods 44 which are connected with the pistons in any suitable manner, as by the ball and socket connections 45. The connecting rods 44 have 105 at their inner ends circular segments 43 which are arranged to slide on the exterior of a ring or bushing 46 and are secured thereto by means of the collars 47 and 48, the latter being secured to the ring 46 by 110

means of screw threads 49 and being held in position by means of a suitable screw 50 which prevents the collar 48 from turning.

The rectangular portion 12^a of the shaft 12 has arranged thereon a ring 51 having a rectangular opening, two faces of which may be arranged to engage opposite faces of the rectangular portion of the shaft. In order to provide for wear, these faces of the 5 ring may be provided with cheek or bearing plates 51^a which fit between the shaft and the ring and cause the ring to be turned by the shaft. The other two faces of the rectangular opening in the ring 51 are spaced apart 10 a sufficient distance to permit the ring to be moved transversely of the shaft 12. Roller bearings 52 are arranged between the rings 51 and 46.

The wedge member 14 is provided with 20 an oblique or wedge portion 53 and secured to this oblique or wedge portion 53 are the laterally projecting keys 54 which engage suitable slots or keyways 55 on the interior of the shaft 12. Wedge blocks 56 and 57 25 are arranged between the ring 51 and the oblique portion 53 of the wedge member and have their inner faces inclined to correspond with the wedge member, whereby the wedge blocks and the ring 51 may be 30 shifted transversely of the shaft 12 by a longitudinal movement of the wedge member 14. The wedge member 14 is also provided with the cylindrical end portions 58 and 59, the former of which is arranged in 35 a suitable cylindrical bore 60 in the shaft 12. The extension 59 of the wedge member projects beyond the end of the shaft 12 and is connected with suitable mechanism for moving the wedge member endwise.

40 The mechanism for moving the wedge member 14 preferably consists of an internally threaded sleeve or cam member 61 which engages an externally threaded or coöperating cam member 62, the latter being 45 connected with the extension 59 of the wedge member by means of two ball thrust bearings 63 and 64. The end of the extension 59 is preferably reduced in diameter as at 65, and beyond the portion 65 is a 50 portion 66 of still smaller diameter forming a shoulder against which is clamped a thrust ring 67 by means of a nut 68, the latter being preferably secured in position by means of a pin 69. The member 62 has an 55 internal recess in which are arranged the thrust bearings 63 and 64, these bearings being held in position by the flange 70 and the threaded hub 71 on the rod 72, this rod being slidably arranged in a suitable bearing 73 supported by the frame 10.

The construction just described, as will be readily understood, permits the wedge member 14 to rotate relative to the rod 72 and the member 62. The sleeve 61 has secured thereto in any suitable manner the

bevel gear 74 which meshes with a corresponding gear 75 on the shaft 76, this shaft being mounted in suitable bearings 77 and 78 and being provided with a suitable hand wheel 79 whereby the shaft may be rotated. 70 A stationary thrust ring 80 may be secured to the frame 10 in any suitable manner and has arranged on the opposite sides thereof the ball thrust bearings 81 and 82, the bearing 81 being preferably in engagement with the back of the bevel gear 74 and both bearings being held in position by means of suitable nuts 83, which are threaded on the exterior of the sleeve 61. As will be readily seen from Fig. 1, the thrust bearings 81 and 82 and the member 62 support the sleeve 61 and hold the same against movement longitudinally of the shaft 12.

The operation of the mechanism is as follows: As shown in Fig. 1, the wedge blocks 85 56 and 57 and the ring 51 are in their central or neutral position so that the ring 46 is concentric with the shaft 12, and therefore when the shaft 12 is rotated the pistons 42 will remain stationary. By shifting the wedge member 14 in either direction from the position shown, it will be seen that the wedge blocks 56 and 57 and the rings 46 and 51 and the connecting rods 44 will be shifted laterally of the shaft and thereby cause 95 the ring 46 to be arranged eccentric to the shaft 12 so that when the shaft is rotated the pistons 42 will be reciprocated in their cylinders 11. It will also be seen that by shifting the wedge member 14 to the right 100 from the position shown in Fig. 1, the ring 46 will be moved downwardly, and by shifting the wedge member 14 toward the left the ring will be moved upwardly so that the direction of movement of the pistons 42 will be reversed in moving the wedge member from one side of the neutral position to the other. Since the eccentric 17, which actuates the valves 30, is fixed to the shaft 12, it will be understood that when the 105 direction of movement of the pistons 42 is reversed the valves 30 will always coöperate to reverse the direction of flow of the water or other fluid which is pumped.

The shaft 12 will ordinarily be driven at 110 a constant speed from any suitable source of power and it is therefore desirable to be able to shift the wedge member 14 without stopping the shaft 12. This may be accomplished by the mechanism which I have disclosed and, as will be readily understood, the member 62 and the wedge member 14, which is connected therewith, will be moved longitudinally of the sleeve 61 when the sleeve is rotated. The rotation of the sleeve 115 61 is effected by means of the hand wheel 79, and the member 62 may be moved in either direction by means of this hand wheel.

It will be observed that all of the working parts are thoroughly inclosed and are 120

so arranged that in case of necessity they may be readily taken apart. By the provision of ball bearings throughout the mechanism very little effort is required on the 5 part of the operator to adjust the mechanism, and the wear on the moving parts is reduced to a minimum.

It will be obvious to those skilled in the art that various changes may be made in the 10 minor details of the invention within the scope of the appended claims and therefore I do not wish to be limited to the precise details of construction shown and described.

Having thus described the invention, what 15 is claimed is:

1. In apparatus of the class described, the combination of a hollow shaft, having a shoulder, a flange spaced therefrom and a through transverse slot between said shoulder and flange, a removable flange arranged in abutting relation to said shoulder, a transversely shiftable eccentric arranged between said flanges and rotatable with said shaft, an axially movable wedge member arranged 20 in said shaft, and means operatively connecting said wedge member with said eccentric.

2. In apparatus of the class described, the combination of a hollow shaft, having a shoulder, a flange spaced therefrom and a through transverse slot between said shoulder and flange, an axially removable flange arranged in abutting relation to said shoulder, a nut on said shaft coöperating with 30 said shoulder to secure said removable flange, a transversely shiftable eccentric arranged between said flanges and rotatable with said shaft, an axially movable wedge member arranged in said shaft, and means operatively connecting said wedge member with said eccentric.

3. In apparatus of the class described, the

combination of a hollow shaft having a rectangular portion and a through transverse slot in said rectangular portion, the shaft 45 also having one or more axially extending internal key-ways, a transversely shiftable eccentric arranged on said rectangular portion of the shaft, an axially movable wedge member in said shaft having one or more 50 keys fitting said keyways, and means operatively connecting said eccentric and wedge member.

4. In apparatus of the class described, the combination of a hollow shaft, having a 55 flange and a through transverse slot adjacent said flange, a transversely shiftable one-piece eccentric ring alongside of said flange and arranged to rotate with said shaft, a removable flange coöperating with the first 60 mentioned flange to hold said eccentric against axial displacement, means for securing said removable flange, and means within said shaft for shifting said eccentric.

5. In apparatus of the class described, the 65 combination of a hollow shaft, having a flange and a through transverse slot adjacent said flange, a transversely shiftable one-piece eccentric alongside of said flange and arranged to rotate with said shaft, an axially removable flange coöperating with the first mentioned flange to hold said eccentric against axial displacement, a second one-piece eccentric on said shaft, a nut threaded 70 on the shaft and securing said second eccentric and removable flange in position, and means in said shaft for shifting the first-mentioned eccentric.

In testimony whereof I affix my signature in presence of two witnesses.

ESTEBAN CIARLO.
